UNITED STATES PATENT OFFICE.

EDWIN L. BERNARD AND HECTOR F. REYNAUD, OF NEW IBERIA, LOUISIANA.

SAFETY COUPLED DRILLING JOINT.

Application filed June 24, 1926. Serial No. 118,326.

This invention relates to drilling joints and more particularly to a connecting joint for use in connecting the drilling tools of well drilling apparatus.

5 An important object of the invention is to provide a device of this character which may be employed to prevent excessive strains upon the drilling tool which would tend to break the same and which, when excessive 10 strains are applied to the drilling tool, serves to disconnect the drilling apparatus and to provide between the drilling apparatus and tool a swivel joint, retaining the connection between the tool and drilling apparatus for longitudinal movements but disconnecting the same during rotative movements.

20 A further and more specific object of the invention is to provide a swivel joint for connecting the sections of drill pipe, particularly that section to which the drill is to be connected to the pipe, the sections of the swivel joint being rigidified to one another by frangible elements, breaking or shearing 25 under strain slightly less than that sufficient to cause breakage of the drill or drill joint.

These and other objects we attain by the construction shown in the accompanying drawings, wherein for the purpose of illustration is shown a preferred embodiment of our invention and wherein:—

Figure 1 is a vertical section through a tool joint constructed in accordance with our invention;

5 Figure 2 is a fragmentary side elevation, the upper section of the joint removed with the pins in position therein;

Figure 3 is a section on the line 3—3 of Figure 1.

0 Referring now more particularly to the drawings, the numeral 10 indicates a cylindrical body having formed in its lower end a threaded box 11 for the reception of the pin 12 which may be either the pin upon the upper end of the drilling tool or upon the upper end of a drill joint of any suitable character. The upper end of the body is formed with a bore 13 which, at a point spaced from the upper end of the box, communicates with a reduced bore 14 extending to the upper end of the box. The connection between the bores 13 and 14 produces an upwardly facing shoulder 15 which is formed with sockets 16, the purpose of which will presently appear. The upper end of the bore 13 is enlarged, as at 17, to

provide a second upwardly facing shoulder 18 and between the shoulder 18 and a point spaced vertically from the shoulder 14, the wall of the bore is threaded, as at 19. The 60 body 10, as described, forms one member of the coupling.

The second member of the coupling consists of a tubular body 20 of less diameter than the bore 13 and having at its lower end 65 a flange 21 increasing its diameter, so that it is equal to the bore 13. The lower end of the body at the thickened or flanged portion thereof is formed with sockets 22 corresponding in number and arrangement to 70 the sockets 16 formed in the shoulder 14. These sockets combine in the assembled relation of the coupling sections for the reception of pins 23 which normally prevent rotation of the sections. The combined 75 shearing strength of the pins 23 is slightly less than the torque factor of the tool or tool pin, so that these pins will shear before the tool will break, in event of the tool jamming in the well. The pins 23 are preferably bi-conic and the sockets 16 and 22 are shaped to receive and fit the ends of the pin. The upper end of the coupling section 20 is threaded at 24 for engagement with a drill pipe coupling 25, by means of which 80 this section of the coupling is connected to the drill pipe 26. The sections of the coupling are maintained in assembled relation by a nut 27 exteriorly threaded to fit the threads 19 of the bore 13 and having an interior bore 28 rotatably receiving the cylindrical body of the section 20. The upper end of this nut has a head 29, the lower face of which seats upon the shoulder 18 when the nut is in applied position and jams there- 85 against to lock the nut in position within the coupling section 10. The head is preferably of sufficient depth to project above the upper surface of the section 10 and in this projecting portion is provided with openings 90 30 in which a wrench may be engaged for seating the nut in the section 10. This nut serves both to prevent vertical displacement of the section 20, which would disengage the pins 23, and to prevent escape of the section 20 therefrom when the pins have been 100 sheared. The bore 14 of the member 10 and the bore of the member 20 serve to provide a water course for connecting the drill pipe with the water course 31 of the tool. 105 110

It will be quite obvious that if, during drilling operations, the tool becomes sud-

denly jammed, with the result that the rotary drilling table (not herein shown) throws a sudden strain upon the drill pipe and tool, before either of these elements will break under the strain thus applied, the pins 23 will shear, permitting the drill pipe to rotate independently of the tool. Since the sudden strain will cause a slowing down of the rotary table and the breakage of the pins will again permit the rotary table to speed up and, in fact, to attain a greater speed than it would ordinarily have, the operator will be immediately apprised of the fact that the breakage has occurred. The tool may then be withdrawn by withdrawing the pipe, the swivel connections serving as a means for hoisting the tool from the hole.

Since the construction hereinbefore set forth is obviously capable of a certain range of change and modification without materially departing from the spirit of the invention, we do not limit ourselves to such specific structure except as hereinafter claimed.

25 We claim:—

In combination with a rotary drilling

pipe and tool to be driven thereby, a coupling connecting the drill pipe and tool including two rotatably engaged sections, one of said sections having a bore reduced to 30 produce a shoulder adjacent its lower end and enlarged to provide a shoulder adjacent its upper end, the other of the sections being of less diameter than said bore and having at its lower end a flange increasing its diameter to the diameter of the bore, said bore being threaded between said shoulders, a nut exteriorly fitting the bore and interiorly fitting the second section, said nut having a head seating upon the second shoulder, the flanged lower end of the second section and the first named shoulder having coacting 35 sockets and pins having their ends arranged in corresponding sockets of the shoulder and the enlarged lower end of the second section 40 and having a combined shearing strength less than the torque factor of either the rotary drilling pipe or tool.

In testimony whereof we hereunto affix our signatures.

EDWIN L. BERNARD.
HECTOR F. REYNAUD.
